HINGED COVER FOR GARBAGE RECEPTACLE
Robert H. Saultz, 552 NE. 34th St.,
Fort Lauderdale, Fla. 33308
Filed Jan. 30, 1967, Ser. No. 612,714
1 Claim. (Cl. 220—36)

ABSTRACT OF THE DISCLOSURE

A combination concrete garbage receptacle and fiberglass cover wherein the cover is hinged to the garbage receptacle by structure including a metal strap bolted to a radial extension of the concrete receptacle, the strap having upstanding spaced brackets apertured to receive a pin, a hollow pedal integral with the cover fitting between the brackets and having holes in the side thereof registering with the apertures of the brackets, a metal pin extending through the holes and apertures in the brackets and pedal, a mastic material filling the hollow space within the pedal and encasing and holding the pin to prevent the same from slipping out of the holes and apertures. Thus, a hinged structure is provided which is compatible with the concrete and fiberglass materials of the receptacle and cover.

This invention relates to a hinged cover for garbage receptacles and has particular reference to a hinged cover that is formed of fiberglass and that completely covers the open upper end of the garbage receptacle having a step-on pedal for swinging the cover to an open position to expose an inner receptacle.

The cover of this invention as before stated, is formed of molded fiberglass and is unbreakable.

Novel features of construction and operation of the device will be more clearly apparent during the course of the following description, reference being had to the accompanying drawings wherein has been illustrated a preferred form of the device.

In the drawings:

FIGURE 1 is a top plan view of the garbage receptacle having the cover hinged thereto,

FIGURE 2 is a side elevational view thereof, and

FIGURE 3 is an enlarged fragmentary section taken substantially on line 3—3 of FIGURE 1.

Referring specifically to the drawings, the garbage receptacle 5 is formed of concrete or the like and is provided with an open upper end. The garbage receptacle is extended at its rear portion as indicated at 6 and has a flat top 7.

The cover, indicated at 8 is formed of fiberglass and is formed in stepped sections 9. The cover 8 has a bottom flange 10 that embraces the open top of the receptacle 5. The rear extension 6 of the receptacle 5 has a flat top 11, receiving a metallic strap 12, that is arcuate upon its inner edge as indicated at 13, to conform to the curvature of the garbage receptacle 5. The strap 12 is held to the flat surface at 11, by a pair of bolts 14 that have fitment into a pair of spaced recesses 15 formed in the extension 6 and with the bolts 15 holding the strap 12 in position by cement or other bonding adjacent that is poured into

2

the recesses 15, to hold the bolts against displacement. The strap 12 is provided with a pair of spaced apart upstanding brackets 16, that are apertured to receive a hinge pin 17 that extends through a pedal 18 and whereby the cover 8 is hinged to the receptacle 5. The cover 8 is molded to form a recess 19 and the side walls of the recess 19, after the hinge pin has been installed through the pedal and the brackets 16, is filled with a mastic composition, such as cement or concrete that covers the hinge pin 17 and prevents the pin from working loose.

In the use of the device, the receptacle 5 is installed in the ground, with the cover 8 being slightly above the ground. An inner receptacle, not shown, is disposed within the hollow of the receptacle 5 and constitutes a receptacle for garbage, trash or the like. When the receptacle is to be open, the user steps upon the pedal 18 swinging the cover 8 upwardly and exposing the inner receptacle. Upon release of the pedal from the foot of the operator, the cover 8 falls to a closed position, embracing the upper open end of the receptacle 5.

The cover 8 being formed of fiberglass, is exceptionally strong with rather little possibility of breaking when the cover is released to fall to a closed position.

It will be apparent from the foregoing that a very novel form of garbage receptacle has been provided. The receptacle 5 is molded in a conventional manner of concrete and the cover 8 being molded in a suitable mold of fiberglass.

The strap 12 and the bolts 15 are securely held within the extension 6 while the hinge pin 17 is encased with concrete or other material that is placed within the recess 18 of the pedal, forming a very strong receptacle and associated mechanism. The device is simple in construction, is exceptionally strong, durable, cheap to manufacture and forms a very desirable garbage receptacle. The cover of this garbage can is light in weight and ordinarily when closing, the collector of garbage or the like merely lets the cover fall to a closed position and, when falling to the closed position, an air cushion is formed within the receptacle, preventing objectionable noise and creates a demand product in large apartment houses, where dozens of cans with the conventional metal covers cause very objectionable noise at removal of the garbage. The cover being formed of fiberglass creates very little noise when moved to the cover position.

It will be apparent from the foregoing that the invention is not limited to the precise construction shown, but that changes are contemplated as readily fall within the spirit of the invention as shall be determined by the scope of the subjoined claim.

I claim:

1. In combination, a concrete garbage receptacle for mounting in the ground with the upper end of the receptacle extending slightly above the ground, said receptacle having generally cylindrical inner and outer side surfaces but having a concrete extension projecting radially from the outer surface thereof to provide a support for hinge means, the extension having a flat top surface flush with the remainder of the upper end of the receptacle, a metal strap affixed to said extension at the top surface thereof and including upstanding metal brackets apertured to receive a pin and spaced apart horizontally, a cover of

fiberglass material having a generally circular configuration for covering the upper end of said receptacle, said cover having as an integral portion thereof a hollow fiberglass pedal projecting from one side of the cover and overlying said extension, said pedal fitting between said brackets and having holes in the sides thereof registering with the apertures of said brackets, a straight pin extending through said pedal and said brackets fitting respectively in said holes and said apertures for hingedly connecting said cover to said brackets, mastic material such as concrete filling the hollow space within said pedal and encasing and holding said pin to prevent the same

slipping out of said holes and said apertures, whereby said fiberglass cover with integral pedal is hingedly connected to said concrete receptacle by structure compatible with the fiberglass and concrete materials thereof.
